UNITED STATES PATENT OFFICE.

WINFIEALD S. LIVENGOOD, OF KANSAS CITY, MISSOURI, ASSIGNOR TO THE SMITH & SONS MANUFACTURING COMPANY, OF KANSAS CITY, MISSOURI, A CORPORATION OF MISSOURI.

WHEELED SCRAPER.

SPECIFICATION forming part of Letters Patent No. 703,800, dated July 1, 1902.

Application filed November 29, 1901. Serial No. 84,121. (No model.)

To all whom it may concern:

Be it known that I, WINFIEALD S. LIVENGOOD, of Kansas City, in the county of Jackson, in the State of Missouri, have invented 5 certain new and useful Improvements in Wheeled Scrapers, of which the following is a full, clear, and exact description, reference being had to the accompanying drawings, which form a part of this specification.

10 My invention relates to certain new and useful improvements in wheeled scrapers, having more particular reference to certain devices for applying the draft directly to the scraper-pan and to certain appliances for 15 facilitating the lifting of the loaded pan and the dumping of the load; and my invention consists in certain features of novelty hereinafter described, and pointed out in the claims.

20 Figure 1 represents a plan view of a wheeled scraper embodying my invention and improvements. Fig. 2 represents a side elevation of the same on a scale somewhat larger than Fig. 1. Fig. 3 represents an end elevation 25 of the same. Fig. 4 represents a detail view of the link by which the draft-bars are suspended from the platform. Fig. 5 represents a detail view of the resilient connection between the axle and the scraper-pan. Fig. 30 6 represents a detail view showing the draft-rod carried under the tongue.

Similar numerals refer to similar parts throughout the several views.

The frame of the scraper consists of an 35 arched axle 1, on which are mounted the wheels 2. On the axle are secured hanger-blocks 3, formed with pockets 4, in which are mounted the side bars 5 and the bail 6. Said side bars extend forwardly and are secured 40 to the tongue 7, and upon the tongue and side bars is mounted a platform 8. The bail is pivotally mounted in said pockets and rocks therein, and extending rearwardly has its ends pivotally secured to ears 9, mounted 45 upon the scraper-pan 10. A hand-lever 11 is secured upon the bail, which, extending forward, is adapted to be engaged by a spring-latch 12, and thereby secured to retain the scraper-pan in elevated position to carry its

load. A stay-bar 13, connected with the axle 50 and secured upon the platform, retains the axle in proper vertical relation, while a rear stay or brace bar 14, connected with the axle, supports and controls the rear of the scraper-pan.

55 15 represents draft-bars connected directly to the scraper-pan. As shown, the connection of said bars with said pan may be by mounting the ends upon the pivot-pin by which the bail is mounted in the ears 9. The precise 60 point of connection, however, is not material. Said bars extending forward are supported by drop-bars 16, pivotally mounted in brackets 17, secured upon the under side of the platform. Links 18 connect said draft-bars with 65 a draft-rod 19, which extends along and beyond the tongue and works loosely in the supporting-eyes 20.

70 With the larger-sized wheeled scrapers where large and heavy loads are to be taken up it is quite usual to attach one or more "snatch-teams"—that is, one or more teams in addition to the team which draws the 75 scraper when loaded and detach the same when the load is taken. With the usual construction of scrapers of this type, in which the draft is applied through the side bars 5 to the axle, the snatch-team is connected with the end of the tongue, and when the scraper-pan is let down to take its load it must be 80 held down by the hand-lever on the bail, and in doing this it is apparent that the pan must be held down against the pull of the team or teams. When, therefore, four or six horses are used to take the load, it is manifest that 85 the labor of holding the pan in the said proper position to take its load is onerous in the last degree, requiring the united and strenuous effort of two or more men. With the device above described, by which the 90 draft of the snatch team or teams is applied directly to the scraper-pan, it will be observed that by reason of the bail having its pivoted point or fulcrum fixed in the hanger-block the draft acts constantly to draw the 95 forward edge of the pan into the soil, so that with such construction one man may easily operate the scraper in taking the load.

When the scraper-pan is loaded, it is obvious that to lift the heavy load taken by the large-sized scrapers above referred to by the use of the hand-lever upon the bail is as difficult and laborious as to hold the pan down in proper position to take its load. To a great measure alleviate this labor and facilitate the lifting of the loaded pan, on the axles I mount standards 21, upon which are mounted spiral springs 22, which springs are connected with the scraper-pan conveniently by a link 23 on the spring engaging an eyebolt 24, secured to the pan. The effect of this construction is that when the pan is let down to take its load the spring is extended and under high tension, and when the loaded pan is to be lifted the action of the spring facilitates the operation to such extent that one man can easily do the work that without the spring would require the united exertion of two or three men. A further efficient function performed by said spring is to relieve the strain or downdraft on the necks of the team attached to the scraper, besides carrying the tongue in this wise. It will be seen that the bail is mounted on the hanger-block in advance of the axle, so that when the load is taken and lifted up the weight of the load, as well as the weight of the men on the platform required to operate the scraper, is carried on the tongue and bears down upon the necks of the horses. This is a very seriously objectionable feature in this type of scrapers. By providing a connection with the scraper-pan to the rear of the axle, as herein shown and described, the load may be balanced over (or under) the axle to a very great nicety. Said connection is made adjustable by connecting the spring with an eyebolt 25, passing through an extension 26 on the standard 21 and provided with an adjusting-nut 27. Another important advantage gained by the use of the spring is in making the dump or dumping the load from the pan. In the usual construction when the dump is to be made the pan is let down; but the greater part of the weight of the load being carried to the rear of the point of suspension of the pan on the bail the rear of the pan, with its load, must be lifted up until the forward edge of the pan is brought into contact with some obstruction sufficiently solid to stop the pan and cause it to turn on its axis. With the device herein set forth when the pan is let down the tension of the spring will hold up the rear of the pan to such extent and in such manner that a very slight obstruction will be sufficient to tilt the pan, thus very greatly facilitating the work of dumping.

If desired, and particularly with the smaller-sized scrapers, the links 18 may be connected with the bolt carrying the doubletree, as shown in dotted lines in Fig. 6, the tongue in such case being slotted, as shown in dotted lines at 28, to permit movement of the doubletree to accommodate the movement of the

pan as it is raised and lowered, and thus, when a single team is used is gained the advantage of the application of the draft directly to the pan, and the leverage due to the relation of the draft-bars 15 to the bail, as hereinbefore set out.

Having thus fully described my improvements, what I claim as my invention, and desire to secure by Letters Patent, is—

1. In a wheeled scraper of the character described, a bail pivotally mounted in advance of the axle, a scraper-pan pivotally hung on said bail to the rear of its point of suspension, a brace-bar connected with the axle and supporting the rear of said pan, and the draft appliances connected directly to said pan whereby as the draft is applied the leverage of the bail tends to thrust said pan into the soil; substantially as set forth.

2. In a wheeled scraper having its scraper-pan carried by a forwardly-extending bail suspended from the axle, and provided with a brace-bar supporting the rear of said pan, draft-bars connected with said pan, and arranged in such manner that as the draft is applied the bail will act to thrust said pan into the soil, substantially as set forth.

3. In a wheeled scraper having its scraper-pan carried by a bail suspended from the axle and provided with a brace-bar supporting the rear of said pan, draft-bars connected with said pan, and links connected with said draft-bars for the application of the draft directly to the pan; substantially as set forth.

4. A wheeled scraper comprising the wheels and axle, side bars connected with the axle and carrying the tongue, a platform mounted on said side bars, a brace-bar supporting the axle, a bail provided with a hand-lever suspended from the axle, a scraper-pan hung on said bail, a brace-bar connected with the axle for supporting the rear of said pan, a latch arranged to engage said hand-lever when the scraper is raised up, and the draft appliances connected with said pan whereby as the draft is applied said bail will act to thrust said pan into the soil, substantially as set forth.

5. In a wheeled scraper having its pan carried by a bail suspended from the axle and provided with a brace-bar connected with the axle for supporting the rear of said pan, draft-bars connected with said pan, links connected with said draft-bars, and a draft-rod connected with said links for the application of a "snatch-team;" substantially as set forth.

6. In a wheeled scraper having its pan carried by a bail suspended from the axle, and a platform carried by side bars connected with the axle, draft-bars connected with said pan, links connected with said draft-bars for the application of the draft, and drop-bars pivotally mounted in brackets secured upon said platform for supporting said draft-bars; substantially as set forth.

7. In a wheeled scraper having its pan carried by a bail suspended from the axle, a rigid

support stationarily mounted on said axle, and a resilient connection between said support and the scraper-pan; substantially as set forth.

5 8. In a wheeled scraper having its pan carried by a bail suspended from the axle, a rigid support stationarily mounted on said axle and extending rearwardly therefrom, and a resilient connection extending from said support 10 to said scraper-pan at the rear of the axle; substantially as set forth.

9. In a wheeled scraper having its pan carried by a bail suspended from the axle, and provided with a brace-bar supporting the rear 15 of said pan, a resilient connection between the axle and said pan; substantially as set forth.

10. In a wheeled scraper having its pan carried by a bail suspended from the axle, standards mounted upon the axle and springs 20 connected with said standards and with said

pan; substantially as and for the purpose set forth.

11. In a wheeled scraper having its pan carried by a bail suspended from the axle, standards mounted upon the axle and springs 25 connected with said standards and with said pan, to the rear of the axle, substantially as and for the purpose set forth.

12. In a wheeled scraper having its pan carried by a bail suspended from the axle, standards mounted upon the axle, springs 30 connected with said standards and with said pan, and means for regulating and adjusting the tension of said springs; substantially as and for the purpose set forth.
